SELF-SHANK BUTTON

René P. Magnenat, Waterbury, Conn., assignor to
the Waterbury Button Company, Waterbury,
Conn., a corporation of Connecticut

Application November 13, 1933, Serial No. 697,706.

4 Claims. (Cl. 24—90)

This invention relates to self-shank buttons and more especially to the construction of the threadholes, shanks, and backs of such buttons.

In self-shank buttons the thread by which the button is fastened to the garment is passed through a transverse hole in the shank. In the performance of its function of securing and holding the overlapping part of a garment flat and smooth upon the overlapped part of the garment it is important to have the button properly spaced from the garment to which it is sewed so that the back of the button will overlie and truly contact the surface of the overlapped piece of the garment in a buttonhole, but if the back of the button stands out too far from the surface of the overlapped part of the garment the back of the button obviously does not serve to press the overlapped part of the garment flat and so wrinkling or bulging of the garment may take place in the buttoned condition thereby detracting from both the appearance and the fit of the garment. From the foregoing discussion it now becomes apparent that in manufacturing self-shank buttons for garments made of relatively thin materials it is important to the perfect functioning of the button in the sewed position on the garment that the shank of the button be short, or in other words that the length of the shank does not greatly exceed the thickness of the garment. If however the button be used on the garment merely for ornamental purposes a short shank on a self-shank button is even more desirable in order to maintain the button in an erect position on the garment. This desired shortness of the shank of the button produces the problem of the threadhole, the problem of providing sufficient strength of material in the shank surrounding the hole, and the problem of a minimum amount of relative movement between the button and the needle in passing the threaded needle through the threadhole and sewing the button to the garment. Studies in this field finally produced a new and distinctive form of threadhole like unto an underriver tunnel in which the inner wall of the threadhole sinks below the surface of the back of the button, with increasingly countersunk approaches starting at points in the back of the button slightly removed from the shank on both sides thereby greatly facilitating the sewing of the button on the garment by providing an easily found and sure guide for the needle point on either side of the threadhole, and in which the outer wall is in the form of a much sharper curve than the inner wall so that the aperture of the hole is enlarged at the entrance on either side of

the shank, thereby permitting the insertion of a needle while it is inclined at an angle either to the plane of the back of the button or to the perpendicular plane through the threadhole, thereby permitting the button to be tipped in a plurality of ways while sewing, but allowing for a substantial and strong body of material sufficient to prevent fracture of the button under stresses on the threads and through them on the part of the shank between the threadhole and the end of the shank. Another important objective is the elimination of the abrasion or cutting of the threads on any sharp-angled edges or protuberances liable to contact the threads. It is also clear that as the length of the shank of the button is increased the length of the countersunk approaches in the back of the button is decreased but that the enlarged apertures remain on both sides of the shank so facilitating and assuring the insertion and passage of a threaded needle through the hole of the shank. The grooved tunnel like approaches may lie entirely within the walls of the shank.

Reference is now made to the drawing, which is hereby made a part of this specification, in which

Fig. 1 is a transverse section in a vertical perpendicular plane through the threadhole.

Fig. 2 is an end view at right angles to that of Fig. 1, and

Fig. 3 is a rear view of the button.

Like numerals of reference refer to like parts throughout the drawing, in which is shown a button 1 made of moldable material such as "bake-lite" having a front surface of any desired design and having a flat or plane-surfaced back 2 from the center of which projects the self-shank 3 through which the threadhole 4 extends transversely. The form of this hole and the form of the construction of the walls are similar in part to a standard subriver vehicular tunnel inverted. On each side of the shank 3 is a countersunk groove 8, each symmetrically positioned with respect to the other, having perpendicular side walls 10 and an inner curved wall 5 so curved on either side as to gradually and increasingly countersink the groove 8 as it merges into the threadhole 4. This inner wall 5 curves in well below the surface of the back 2 and emerges symmetrically on the opposite side of the shank 3, so that the entrances to the threadhole are symmetrical. The outer wall 6 of the threadhole 4 in the intermediate portion thereof is a curve of much shorter radius than that of the inner wall 5 and at either end the wall 6 terminates in a

60

70

75

80

85

90

95

100

105

110

curve 11 tangentially related to a vertical plane through the end of the wall. When the end of the shank is flat the centers of these curves 11 forming the ends of the wall 6 lie in the plane of 5 the end of the shank 3, so the perpendicular aperture or vent 9 to the threadhole 4 is open-mouthed at either end and yet a substantial wall of material at the central point of the shank overlies the threadhole 4. The importance of this construction 10 becomes selfevident when it is understood that when the button is sewed to a garment the threads overlie the wall 6 of the threadhole 4 so that strength is essential at the central part of the shank 3 to prevent fracture of the shank due 15 to stresses on the threads. It will be noted also that this construction permits the threads to lie down close near the end of the shank 3, which is substantially flat, thereby holding it securely in the fixed position of the garment. These small-radius curves 11 assure complete elimination of 20 any liability at either opening of the threadhole of a sharp or angled edge abrading or cutting any thread used to fasten the button to a garment. The flat end 7 of the shank 3 insures that the 25 button will securely stand erect in a perpendicular position on the garment. The countersinking of the inner wall 5 below the back 2 serves two important functions; first, it permits a short self-shank 3 with ample moldable material between 30 the threadhole and the end of the shank to resist fracture or rupture caused by the stresses on the threads which fasten the button to the garment; and second, it permits a wide variation in the angle of insertion of a threaded needle without 35 danger of breaking the point, which in turn gives a greater factor of safety in the operation of sewing on a button. It will also be clear that in sewing on a button the needle point will tend to engage the surface 8 and travel along this surface and so be clear and away from threads already laid over the wall 6 of the threadhole so 40 that in repassing through the threadhole the needle point does not pass through any of the thread already laid. These same two functions attested above are similarly served by the enlarged vent or aperture 9. The curved walls 11 45 eliminate any sharp edges or angles liable to abrade or break a thread. The grooved countersink 8 on either side of the shank 3 serves as a guide to the needlepoint and further enhances the factor of safety in sewing on a button. This factor of safety is also an assurance of efficiency in preventing the needlepoint from missing the threadhole because of any tilting of the button with 50 reference to the garment. The perpendicular walls 10 of the groove 8 act as stops and so hold the needlepoint surely in the groove.

Having disclosed one embodiment of my invention and having depicted the manner of its use it 55 will be understood that modifications in the size, form or design may be made by any mechanic 60

65

70

75

skilled in the art within the spirit and scope of my invention and that I do not limit myself except as in the appended claims.

I claim:

1. A self-shank button for clothing formed of an integral piece of moldable material comprising in combination, a disc-like portion having a plane-surfaced back, a shank extending centrally and rearwardly from the back, and a transverse threadhole through said shank, the inner wall of the threadhole at the center lying below the back of the button and the outer wall of the threadhole being formed in a much sharper curve than the inner wall whereby the aperture of the threadhole on either side is substantially larger than the central part of the threadhole. 80

2. A self-shank button for clothing formed of an integral piece of moldable material comprising in combination, a disc-like portion having a plane-surfaced back, a shank extending centrally and rearwardly from the back, a transverse threadhole through said shank, the inner wall of the threadhole at the center lying below the back of the button and the outer wall of the threadhole being formed in a much sharper curve than the inner wall whereby the entrance to the threadhole on either side is substantially larger than the central part of the hole, and increasing- 85
